UNITED STATES PATENT OFFICE.

WILLIAM R. BATES, OF FLINT, MICHIGAN.

DESIGN FOR A LAMP, GAS, AND ELECTRIC-LIGHT GLOBE OR SHADE.

SPECIFICATION forming part of Design No. 14,264, dated September 11, 1883.

Application filed December 22, 1882. Term of patent 14 years.

To all whom it may concern:

Be it known that I, WILLIAM R. BATES, a citizen of the United States, residing at Flint, in the county of Genesee and State of Michigan, have invented and produced a new and original Design for a Globe or Shade for a Lamp, Gas-Jet, Electric Light, or other Artificial Source of Illumination, reference being had to the accompanying photograph, forming a part of this specification.

Heretofore globes or shades for lamps and other sources of artificial light have been ornamented with tracery, arabesque work, landscapes, representations of animals, flowers, &c.

The object of this present design is to furnish a globe or shade having represented upon its surface, either in colors or in any other way known to the art, a map exhibiting the geography of the world, or a portion thereof, the same forming a design of a highly ornamental, original, and novel appearance, which may at the same time possess utility and interest as a means of ready reference. The

globular form of the shades most preferred and their illumination from within peculiarly adapt them to the display of this style of ornamentation, which can only be correctly shown on a spherical surface.

I do not claim to have made any mechanical improvement in lamp-shades; nor any discovery or invention in the art of tracing, etching, engraving, embossing, molding, printing, or otherwise producing impressions upon glass surfaces; nor to have invented a transparent map.

What I claim is—

The design for a globe or shade for a lamp or other source of artificial light herein described, consisting of a translucent globular shade having represented upon its surface a map of the world, or a portion thereof, substantially as specified.

WILLIAM R. BATES.
